DESIGN FOR A LANTERN GLOBE

Shigeyuki Mimura, Westfield, N. J.

Application February 6, 1935, Serial No. 55,270

Term of patent 7 years

To all whom it may concern:

Be it known that I, Shigeyuki Mimura, a subject of the Emperor of Japan, and resident of Westfield, in the county of Union and State of New Jersey, have invented a new, original, and ornamental Design for a Lantern Globe, of which the following is a specification, reference being had to the accompanying drawing forming a part hereof.

In the drawing, Fig. 1 is a perspective view of a lantern globe, showing my new design; Fig. 2 is a side elevation thereof; and Fig. 3 is a top plan view thereof.

I claim:

The ornamental design for a lantern globe, as shown.

SHIGEYUKI MIMURA.
